PACKAGE SMOOTHING APPARATUS

George B. First, Philadelphia, Pa., assignor to
 Stokes and Smith Company, Philadelphia, Pa.,
 a corporation of Pennsylvania

Application April 17, 1933, Serial No. 666,391

9 Claims. (Cl. 93—2)

My invention relates to apparatus for smoothing or eliminating blisters from wrapped packages, containers, boxes or the like.

In accordance with my invention, after the packages have been wrapped and while the adhesive on the wrappers is still unset, the corners are wiped or ironed to ensure contact of the wrapper at these regions; more particularly, the packages leaving the wrapping machine are received by a conveyor which transports them along a path provided with presser-blocks suitably shaped to receive and smooth the package corners.

My invention also resides in the features of construction, combination, and arrangement hereinafter described and claimed.

For an understanding of my invention and for illustration of a preferred form thereof, reference is to be had to the accompanying drawings, in which:

20 Fig. 1 is a front elevational view of a package wrapping system utilizing my invention.

Fig. 2 is a plan view of the apparatus shown in Fig. 1.

25 Figs. 3 and 4 in perspective, illustrate blister formation at the corners of packages wrapped in accordance with the prior art.

Fig. 5 is a detail view, on enlarged scale, of the smoothing attachment of Figs. 1 and 2.

Fig. 6 is an end elevational view with parts 30 in section of the attachment shown in Fig. 5.

Fig. 7 in perspective, shows the corner of a package and illustrates the result of operation of the mechanism shown in Figs. 5 and 6.

Referring to Figs. 1 and 2, the machine G may 35 be of any suitable known type for wrapping packages, and therefore its construction and method of operation are only briefly described. The machine for example may be of the type described in Patent No. 1,599,154, Weightman et al.

40 Packages P on the receiving conveyor C are moved to the right, the plate 1 engaging the first package of the series, to arrest movement of all of them. The conveyor C1 is provided with plates 2 spaced at suitable intervals, which in turn lift

45 the foremost package of the series to the platform 3. As soon as one package is removed by conveyor C1, the belt conveyor C advances the series of packages until the next package is arrested by the stop 1 for removal by the next

50 plate 2.

The packages are pushed from the plate 3 onto the supporting bars 4, 4. On opposite sides of the bars are the endless conveyors C2, C3 each having extending outwardly therefrom a series of 55 spaced pusher elements 5 each adapted to co-

operate with the like opposite elements of the other conveyor to push a package along a path through the machine from left to right.

The conveyors are timed with respect to the wrapper applying roll R1 which is provided with a gripper 6 to receive wrappers W removed from the stack S by the feeding element 7. The upper wrapper separated from the stack is fed by the rolls 8 through the guide 9 over the adhesive applying roll 10 into the open gripper jaws. By mechanism, not specifically shown the gripper 6 then closes and carries the wrapper into engagement with the lower face of a package P, whereupon the gripper 6 is opened, so that the wrapper is free to move with the package P.

As each package in turn approaches the right end of the conveyor it is pushed downwardly by the plunger 11 which effects engagement between the panel S of the wrapper, and the corresponding side of the package so that at this stage two sides of the package are covered. The intermittently rotated turret 12 carries the packages through several stations where the remaining panels of the wrapper are applied; the wrapped packages are ultimately delivered to a position between the conveyor belts C4, C4 which engage the opposite ends of the packages to slide them along the supports 13 for discharge at the right-hand ends of the belt.

Machines of this type are usually operated at high speed, for example, the rate of about 60 to 65 packages per minute, and it is characteristic of most packages wrapped by them, that at the edges or corners of the packages there are blisters, or wrapper portions not adhesively secured to the package body, which not only mar the appearance of the packages, but are also objectionable for the reason that the wrapper is particularly susceptible to being torn or broken at these regions. Figs. 3 and 4 illustrate the blistered condition characteristic of the corners of packages wrapped by machines now in common use. The wrapper instead of passing tightly around the package is bulged leaving a loose fold embracing but not attached to the corner.

In accordance with my invention as the wrapped packages pass beyond the discharge conveyors C4, they fall upon the conveyor C5 of smoothing attachment I, preferably driven, as by gears 14, 15 and shaft 16 from the wrapping machine G, at a speed slightly higher than the speed of belts C4.

As each package moves to the left, as viewed in Fig. 5, it is aligned on the belt C5 by the guide

plates 17, 18. The narrow belts c5 on either side of the main belt C5 cooperate with the guides 17 and 18 in turning into alignment any package which may have fallen to greater or lesser extent on the belt C5. The adjustable stop 19 having a transverse portion 20 extending above the belt at a height slightly greater than the height of the package, holds back any package that may be traveling in the inclined position indicated by dotted package P1, so that it will fall on to the belt in back of and in the same plane as the preceding package. As each package continues to move to the left it passes below and into engagement with the belt C6 driven from shaft 21 of gear 14 through the train of gears, 22, 23, 24, 25.

The bar or plate 26 as shown in Figs. 5 and 6, carries a plurality of rolls 27 which bear against the upper surface of the lower lift of the belt C6 to press the packages downwardly against the similar rolls 28 which support the upper lift of belt C5. At each end, the bar 26 is provided with a plate 29 having upwardly extending guide rods 30 which pass through suitable openings in the plates 31 extending between the side frames 32 of the machine. The rollers therefore are in effect resiliently mounted to yield as the packages are transported by and between the belts. The lower set of rollers 27' are similarly mounted upon a bar 26' supported from the side frames 32.

As a package is fed to the left by the belts, its leading end enters the space or opening defined by four presser blocks 33 each comprising a shoe 34 whose receiving end is flared to facilitate reception of the package. The blocks are adjusted so that the shoes, as most clearly appears in Fig. 6 define the four corners of a rectangle closely approximating the outside dimensions of the package P. Preferably before entrance of a package these shoes define a rectangle less than the rectangular outline of the package, and as the package enters, these shoes are moved outwardly against the resistance offered by suitable resilient means, for example springs 35, or sponge rubber blocks 36. These shoes, as the package is moved along by the belts C5, C6 iron down any wrapper blisters at the corners X of the package, and as the adhesive on the wrapper is still unset, the wrapper remains attached after the package passes beyond the shoes.

If complete elimination of the blisters is attempted to be effected by one set of presser blocks, it may be necessary to use such high pressure that movement of the packages by the belts is difficult. Accordingly, therefore, the first set of presser blocks 33 is adjusted to have relatively light pressure and the package after leaving these blocks passes to a second set of similar presser blocks adjusted so that the spacing between the blocks is somewhat less, or in other words, so that the pressure exerted at the corners of the package is somewhat higher. In some cases, it may be desirable to use a third set as shown, all depending upon the nature of the material within the package and its ability to support the walls of the package against pressure.

As shown most clearly in Fig. 6, each presser block is capable of movement or adjustment in three directions. The slot 37 in the supporting bracket 38 permits movement of the block toward and away from the center of the belts. The block is held in its adjusted position by tightening of the screw 39. Each block may be adjusted vertically to accommodate packages of different height or thickness, by reason of the slot 40 in

the bracket 38 through which extends the bolt 41. The slots 42 in the upper and lower frame members 43, 44 permit the blocks to be spaced at greater or lesser distances along the conveyor C5.

The side frames 32 are mounted upon or concentric to the shaft of gear 25 and the driving roll of belt C6 so that by loosening of nuts 50 or equivalent, the structure comprising frame 32, belt C6, bar 26, rolls 27, and the upper presser blocks can be swung upwardly to facilitate access to the presser blocks, etc. This movement, which can be effected by displacement of handle 51, does not effect disengagement of the gears 24, 25.

After passing through my attachment, the packages are tightly wrapped, each wrapper snugly engaging the corners of its box P, as shown by Fig. 7.

Packages are often double wrapped, i. e., it is first wrapped with craft paper, for example, and thereafter again passed through the same or a similar machine for application of a printed or decorative wrapper. As shown by Fig. 4, for this double wrapping the blistering at the corners is more pronounced. By recourse to my attachment, the blisters can be smoothed or eliminated for the double wrapped package by passing the package through the attachment after each wrapping, or if two wrapping machines are used each should have the ironing attachment.

While I have illustrated a preferred arrangement, it is to be understood that my invention is not limited thereto but corresponds in scope to the appended claims.

What I claim is:

1. Apparatus comprising a conveyor for transporting freshly wrapped packages, and a plurality of independently and resiliently mounted structures each adapted to embrace a side corner of the package for smoothing of wrapper blisters during movement of the package by the conveyor by engagement with adjoining side faces of the package at and adjacent their junction.

2. The combination with a machine for adhesively applying wrappers to packages and having a discharge conveyor, of a conveyor for receiving the discharged packages and operating at higher speed than said discharge conveyor, and devices adjacent the path of movement of packages on said second conveyor for smoothing of the side corners of the wrapped packages before setting of the adhesive.

3. The combination with a machine for adhesively applying wrappers to packages and having a discharge conveyor, of a conveyor belt for receiving the discharged packages, a second belt for engaging the upper surfaces of said packages overlying said first belt and terminating short of said discharge conveyor, and devices adjacent the path of movement of packages between said belts for smoothing the side corners of the packages before setting of the adhesive.

4. Apparatus comprising a conveyor for transporting freshly wrapped packages, and means for smoothing the side corners of said packages to remove wrapper blisters comprising a plurality of members, each adapted simultaneously to wipe adjacent side faces of the package at and adjacent their junction forming a side corner.

5. Apparatus comprising a conveyor for transporting freshly wrapped packages, means for smoothing the side corners of said packages to remove wrapper blisters comprising means for mounting individual of said elements to permit movement thereof normal to either or both of

the faces engaged thereby, and yielding means resisting said movement.

6. Apparatus comprising a conveyor for transporting freshly wrapped packages, means for smoothing the side corners of said packages to remove wrapper blisters comprising a group of four elements defining the four corners of a rectangular passage somewhat less in height and width than the ends of the packages, and each having surfaces extending parallel to adjacent side faces of the conveyed packages, and means permitting said elements to yield individually as each package is conveyed through said rectangular passage, said surfaces of each of said elements wiping adjoining side faces of the packages at and adjacent their junction.

7. Apparatus comprising a conveyor for transporting freshly wrapped packages, means for smoothing the side corners of said packages to remove wrapper blisters comprising a group of four elements defining the four corners of a rectangular passage somewhat less in height and width than the ends of the packages, and each having surfaces extending parallel to adjacent side faces of the conveyed packages, means permitting said elements to yield individually as each package is conveyed through said rectangular passage, said surfaces of each of said elements wiping adjoining side faces of the packages at and adjacent their junction, a second group of elements subsequently engaged by the conveyed packages and defining the four corners of a rec-

tangular passage somewhat less in height and width than said first passage, each of said elements of said second group having surfaces for wiping adjoining side faces of the packages at and adjacent their junction, and means for yieldingly and individually supporting the elements of said second group.

8. Apparatus comprising means for conveying packages comprising a pair of belts for engaging opposite faces of the packages, a movable frame for supporting one of said belts, a group of elements defining the four corners of a rectangular passage between said belts somewhat less in height and width than the ends of the packages and each having surfaces for wiping the adjoining side faces of the package at and adjacent their junction, and means for yieldingly supporting a pair of said elements upon said frame.

9. Apparatus for conveying packages comprising a pair of belts for engaging opposite faces of the packages, a group of elements defining the four corners of a rectangular passage between said belts somewhat less in height and width than the ends of the packages and each having surfaces for wiping the adjoining side faces of the package at and adjacent their junction, driving and driven gears for moving one of said belts, and a frame for supporting said one of said belts and certain of said elements pivotally mounted concentric to the axis of the driven gear.
